UNITED STATES PATENT OFFICE.

CLARENCE A. BAGGS AND ALEXANDER B. CUMMIN, OF SAN JOSE,
CALIFORNIA.

SAW-SET.

SPECIFICATION forming part of Letters Patent No. 695,135, dated March 11, 1902.

Application filed August 5, 1901. Serial No. 70,888. (No model.)

To all whom it may concern:

Be it known that we, CLARENCE A. BAGGS and ALEXANDER B. CUMMIN, citizens of the United States, residing at San Jose, in the 5 county of Santa Clara and State of California, have invented certain new and useful Improvements in Saw-Sets, of which the following is a specification.

Our invention relates to improvements in 10 saw-sets, the object of our invention being to provide a device of this character which shall be simple and rapid in operation and accurate and effective in its results.

Our invention therefore resides in the novel 15 construction, combination, and arrangement of parts for the above ends hereinafter fully specified, and particularly pointed out in the claims.

In the accompanying drawings, Figure 1 is 20 a front elevation of the device. Fig. 2 is a rear view of the same. Fig. 3 is an end view of the same. Fig. 4 is a cross-section, and Fig. 5 is a detail, of the clamping-cam.

Referring to the drawings, 1 represents a 25 casting or frame which can be secured to a bench through screw-holes 2. On dovetailed ways 3 on said frame 1 slides the carriage 4, carrying the hammer 5 for setting the saw-teeth. Said hammer reciprocates vertically 30 in bearings 6 and is normally raised by a coiled spring 7. Said carriage has formed on its under surface a rack 8, engaged by a pinion 9 on a shaft 10, which shaft has bearings in the casting and also in a block 11, secured 35 to said casting, said shaft carrying on its outer end a milled head 12 for turning said pinion. The turning of the milled head 12 thus operates the rack 8 and reciprocates the carriage to bring it over the saw-teeth in suc- 40 cession.

14 represents a spring-clamp having guide-pins 15 attached thereto sliding in suitable vertical slideways in the block 11. The saw is secured beneath said clamp and above an 45 anvil 16, adjustable in the casting or frame 1, by means of a screw 17. For pressing down the spring-clamp 14 to secure the saw in position there is provided a clamping-cam 18, operated by a handle 19. Said clamping-cam 50 18 works in a slot 17, cut through the block 11, and is rotatable on the shaft 10 as a pivot. In operation the saw is placed between the

anvil 16 and the clamp 14, so that the teeth are in position beneath the hammer 5, and said clamp is then pressed down by means of 55 the cam 18. A blow is now given to the hammer to set a tooth, and then by rotating the pinion 9 to a suitable extent the carriage is moved through the proper distance to bring the next tooth in position, when the hammer 60 is again struck, and so on for the remaining teeth of the saw.

We claim—

1. In a saw-set, the combination, with the frame, of a carriage slidable thereon, means 65 for sliding said carriage, a hammer movable vertically in the carriage, a spring retracting said hammer, an anvil, a vertically-movable spring-clamp, and means for depressing said clamp, substantially as described. 70

2. In a saw-set, the combination, with the frame, of a carriage slidable thereon, means for sliding said carriage, a hammer movable vertically in the carriage, a spring retracting said hammer, an anvil, means for moving the 75 same laterally, a vertically-movable spring-clamp, and means for depressing said clamp, substantially as described. 75

3. In a saw-set, the combination, with the frame, of a carriage slidable thereon, means 80 for sliding said carriage, a hammer movable vertically in said carriage, a spring retracting said hammer, an anvil, a vertically-movable clamp, and a cam for depressing said clamp, substantially as described. 85

4. In a saw-set, the combination, with the frame, of a carriage, slidable thereon, and carrying a rack, a hammer movable in vertical slideways in said carriage, a spring retracting said hammer, an anvil adjustable laterally of 90 the frame, a spring-clamp a shaft and a pinion thereon engaging the rack on the carriage, and a clamping-cam pivoted on said shaft, said cam engaging the clamp to press the same down in position, substantially as described. 95

In witness whereof we have hereunto set our hands in the presence of two subscribing witnesses.

CLARENCE A. BAGGS.
ALEXANDER B. CUMMIN.
